DESIGN FOR A GAME BOARD

Edward Schell, Machias, N. Y.

Application May 21, 1945, Serial No. 119,642

Term of patent 7 years

(Cl. D34—5)

To all whom it may concern:

Be it known that I, Edward Schell, a citizen of the United States, residing at Machias, in the county of Cattaraugus and State of New York, have invented a new, original, and ornamental Design for a Game Board, of which the following is a specification, reference being had to the accompanying drawing forming part thereof.

I claim:

The ornamental design for a game board, as shown.

EDWARD SCHELL.
